US0D1007306S

(12) **United States Design Patent** (10) Patent No.: **US D1,007,306 S**
(45) Date of Patent: ** Dec. 12, 2023

(54) **LID FOR PACKAGING**

(71) Applicant: **TETRA LAVAL HOLDINGS & FINANCE S.A.**, Pully (CH)

(72) Inventors: **Pietro Martini**, Parma (IT); **Francesca Tavoni**, Modena (IT); **Maurizio Filippini**, Modena (IT)

(73) Assignee: **TETRA LAVAL HOLDINGS & FINANCE S.A.**, Pully (CH)

(**) Term: **15 Years**

(21) Appl. No.: **35/514,312**

(22) Filed: **Nov. 16, 2021**

(80) **Hague Agreement Data**

Int. Filing Date: **Nov. 16, 2021**

Int. Reg. No.: **DM/217546**

Int. Reg. Date: **Nov. 16, 2021**

Int. Reg. Pub. Date: **May 20, 2022**

(30) **Foreign Application Priority Data**

May 18, 2021 (EM) 008544902

(51) LOC (14) Cl. **09-07**

(52) **U.S. Cl.**

USPC **D9/446; D9/452**

(58) **Field of Classification Search**

USPC D7/392.1, 396.2; D9/434-436, 444, 499, D9/440, 443, 446, 447, 400, 452-454

CPC B65D 5/746; B65D 5/563; B65D 47/0847
